CLAIM

The ornamental design for a water processing machine, as shown and described.

DESCRIPTION

FIG. 1 is a perspective view of a water processing machine.
FIG. 2 is a front view of the water processing machine.

FIG. 3 is a rear view of the water processing machine.

FIG. 4 is a right side view of the water processing machine.

FIG. 5 is a left side view of the water processing machine.

FIG. 6 is a top view of the water processing machine; and,
FIG. 7 is a bottom view of the water processing machine,
which is disclaimed.

In the drawings, the broken lines depict portions of the article that form no part of the claimed design.
